J. F. Bartlett:

UNITED STATES PATENT OFFICE.

JAMES F. BARTLETT, OF CHICAGO, ILLINOIS, ASSIGNOR TO THE CHICAGO CASH CARRIER COMPANY, OF ILLINOIS.

CASH-CARRIER.

SPECIFICATION forming part of Letters Patent No. 483,681, dated October 4, 1892.

Application filed May 12, 1892. Serial No. 432,755. (No model.)

To all whom it may concern:

Be it known that I, JAMES F. BARTLETT, of Chicago, county of Cook, and State of Illinois, have invented a new and useful Improvement in Cash-Carriers, of which the following is a specification.

My invention relates to that class of cash and parcel carriers designed mainly for store-service, in which a wheeled carrier provided with a detachable box or receptacle is arranged to travel to and fro on a sustaining-wire.

The invention has in view the simplification of the apparatus, the stoppage of the carriage at the end of its movement with certainty and in a noiseless manner, and the propulsion of the carriage by a manual device operating without the assistance of springs, catches, or other complicated devices. With these ends in view I provide at each end of the wireway a buffer consisting of a collapsible sack or chamber provided with a shoulder or its equivalent to interlock with the incoming car. I construct the car with a frame, the ends of which encircle the sustaining-wire and which are adapted to automatically engage with the shoulder of the buffer as the car reaches the terminal station.

For the purpose of propelling the car I make use of a handle or handpiece, consisting simply of an arm having one end adapted to loosely encircle the wire, so that it may be suspended freely thereon when not in use, and carried forward against the car with a sweeping motion to impel the car over the line, as hereinafter more fully explained.

Referring to the accompanying drawings, Figure 1 represents in side elevation the car, one end of the sustaining-wire, the buffer, and its connections. Fig. 2 is top plan view of the car. Fig. 3 is a longitudinal central vertical section through the parts represented in Fig. 1. Fig. 4 is a perspective view of the propelling device; and Fig. 5 is a cross-section on the line 5 5, Figs. 1 and 2.

In carrying my invention into effect I extend a wire or cord A under suitable tension between the counter and the cashier's desk or other terminal stations, securing the same at

its ends by turnbuckles or equivalent devices 50 to a supporting wall or standard. On this wire I mount permanently the traveling car or carriage B, provided with two sustaining-wheels B², arranged to ride upon the wire, so that the car may move with ease and freedom. 55

To the car I connect a detachable cup or receptacle B', designed to receive the change or other articles to be transported. This cup may be attached to the car in any suitable manner. As represented in the drawings, the cup is provided at the upper edge with projecting studs or pins arranged to enter L-shaped slots in a circular flange on the bottom of the car, after the manner of a bayonet- 60 joint.

At each end of the line I provide a buffer D in the form of a collapsible chamber of rubber or other elastic material. These buffers are preferably mounted upon and around the wire A, as shown in the drawings, in order that it may serve as a support therefor. At their rear sides these chambers are preferably fixed upon the wire but at the forward side or side toward the car they are each formed 70 with a projecting neck or shoulder d', arranged to slide freely around the wire and adapted to serve as a buffer or cushion against which the end of the incoming car may impinge. To the neck of the buffer I attach an outwardly-extending tube sliding freely around the wire and terminating at its outer end in a conical head C, having an annular shoulder c at its inner end. The frame of the carriage is adapted to encircle the 75 wire at its two ends, and is provided at the end with openings a of sufficient size to permit the head C to pass therethrough and to permit the carriage to be lifted independently to disengage it from the head. As the car 80 approaches the terminal point the end of its frame rides over the head C upon the neck c' and against the neck of the buffer, which, yielding by reason of its elasticity and by

reason of the leakage of air through the neck, 85 serves to arrest the momentum of the car in an easy and noiseless manner. The end of the car, after passing over the neck, falls be- 90 95

hind its shoulder *c* in the manner indicated in Fig. 3, whereby the car is prevented from rebounding and returning along the line.

Each end of the car-frame is extended upward and outward in the form of an ear *a'*, by means of which the end of the frame may be lifted so as to disengage the same from the shoulder *c*, that the car may be driven forward on its return-course. This unlocking of the car and its impulsion over the line may be effected by hand or by mechanism of any suitable character; but I recommend the employment of an impelling device substantially such as shown in Fig. 4, consisting of a bent rod or wire provided with a suitable handle at the lower end and having its upper end bent into the form of a ring, preferably with an opening on one side that it may be conveniently hooked upon or removed from the wireway. I commonly engage this device around the wire at or near the buffer *D*, between the buffer and the carriage. When the carriage is to be driven forward, the handle of the impelling device is grasped and its upper end engaged, as shown in dotted lines in Fig. 1, beneath the lip *a'* of the carriage, so as to lift the latter over the neck *c'*, thus leaving the carriage free. As a continuation of the same action and with a sweeping or swinging motion the upper end of the arm is carried forward against the rear end of the carriage, which is thereby caused to advance over the line with sufficient velocity to reach the station at the opposite end.

It will be observed that the conical head *C* is in effect simply a detent or catch to hold the car from reacting after contact with the buffer, and it is apparent that it may be modified in form within the range of mechanical skill, provided it is adapted to operate with essentially the effect described, the only essential requirement being that the car and the detent shall be adapted to unlock automatically.

It is evident that the operativeness of my apparatus is not affected by the lateral swinging or vibration of the carriage, and that the latter will engage the detent whether hanging vertically or swung to one side; also, that when engaged with the detent it may be swung laterally to any extent without danger of becoming disengaged, since the returning-shoulder extends entirely around the neck.

Having thus described my invention, what I claim is—

1. In a cash-carrier, the combination of a way, a car arranged to travel thereover, a collapsible elastic buffer in the path of the car

to arrest its motion, and a detent adapted to engage the car and prevent the same from rebounding.

2. In a cash-carrier, the combination of a way, a wheeled car movable thereover, a collapsible buffer at the end of the line to arrest the advancing car, and a detent connected to the buffer and adapted to engage the car and prevent its rebounds.

3. In a cash-carrier, the combination of the wire, the car mounted thereon, the collapsible chamber or buffer, and the shouldered neck attached to the chamber or buffer and adapted to engage and hold the car.

4. In a cash-carrier, the combination of the wireway, a car movable thereon, a collapsible elastic buffer mounted on and sustained by the wire to check the movement of the advancing car, and the shouldered neck connected to the buffer and adapted to enter an opening in the car and interlock therewith.

5. In a cash-carrier, the combination of the wireway, the shouldered neck or detent thereon, the carriage provided with the opening to admit the detent and with the lip projecting longitudinally beyond the carrier by which to lift the latter out of engagement, and a lifting device on the way for raising the carriage.

6. In a cash-carrier, the wireway and the car thereon, in combination with the collapsible chamber having the tubular neck, and the conical head or detent adapted to slide loosely upon the wire.

7. In a cash-carrier, the combination of a wireway or track, an annular shouldered detent thereon encircling the same, and a carriage having in its end a shouldered opening 95 to receive and engage said detent.

8. In a cash-carrier, the combination of a wireway or track, a detent encircling the same and comprising a cylindrical neck and a tapered head, and a carriage having in its end 100 a shouldered opening to receive and engage said detent and capable of swinging around the same.

9. In a cash-carrier, and in combination with a way and a car thereon, a buffer consisting 105 of an elastic sack provided with a vent to permit the escape of air under the impact of the car.

In testimony whereof I hereunto set my hand, this 12th day of May, 1892, in the presence of two attesting witnesses.

JAMES F. BARTLETT.
